(57) **CLAIM**

The ornamental design for a protective case for mobile device, as shown and described.

DESCRIPTION

FIG. 1 is a back and right side perspective view of a protective case for mobile device in accordance with our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, back and right side perspective view of the protective case for mobile device shown in a condition for use.

The smaller spaced broken lines and the larger spaced broken lines depict portions of the protective case for mobile device which form no part of the claimed design.

1 Claim, 4 Drawing Sheets
